(57) **CLAIM**

We claim the ornamental design for a laminator, as shown and described.

DESCRIPTION

FIG. 1 is a front isometric view of the laminator, showing my new design;

FIG. 2 is a front-elevational view of the laminator;

FIG. 3 is a top view of the laminator;

FIG. 4 is a right side-elevational view of the laminator;

FIG. 5 is a left side-elevational view of the laminator;

FIG. 6 is a rear-elevational view of the laminator; and,

FIG. 7 is a bottom view of the laminator.
